UNITED STATES PATENT OFFICE.

JOHNNY G. C. AKERS, OF WALLACE, NEBRASKA.

MERRY-GO-ROUND.

Application filed December 11, 1926. Serial No. 154,194.

This invention relates to merry-go-rounds and has for an important object thereof the provision of a device of this character which is propelled by the occupants thereof.

5 An important object of the invention is to so construct the device that it may be readily propelled and that rotation thereof may be readily checked by an occupant.

A further object of the invention is to 10 improve the construction of merry-go-rounds of this type, as regards the placement of the necessary supporting seats and races therefor to permit the seats to act to prevent displacement of the braces, due to the strains to which 15 devices of this character are subjected.

A further object of the invention is the provision of a device of this character of such construction that bearings about which the device rotates are fully protected from the 20 weather.

A further object of the invention is to provide a device of this character which will be readily and cheaply constructed and which will be durable and efficient in service.

25 These and other objects I attain by the construction shown in the accompanying drawings, wherein for the purpose of illustration is shown a preferred embodiment of my invention and wherein:

30 Figure 1 is a plan view of a merry-go-round constructed in accordance with my invention;

Figure 2 is a section on the line 2—2 of Figure 1;

35 Figure 3 is a section on the line 3—3 of Figure 2;

Figure 4 is a fragmentary side elevation showing the manner of connecting the seat boards to the arms and braces;

40 Figure 5 is a plan view of the ends of the seat boards and the plates applied thereto.

Referring now more particularly to the drawings, the numeral 10 generally designates a base, at the center of which is arranged 45 a casting 11 having a central upstanding circular flange 12. The body of this casting is connected with the outer corners of the base by braces 13. Seated at its lower end upon the casting 11 and fitting within bearing 11^a is a vertical shaft 14 and a tube 15 surrounds the lower end of this shaft and fits against and is threaded to the flange 12. The upper end of the tube provides a seat for a rotor base 16 which has an aperture 17 through which the

shaft 14 is directed and has about this aperture 55 at its lower face a flange 18 into which the upper end of the tube is threaded. The rotor base 16 is preferably connected with the outer ends of the braces 13 and with the base by braces 19. Upon the upper surface of the 60 rotor base is formed a circular flange 20 which is spaced from the edges of the opening 17 to provide a housing for a thrust bearing 21.

The numeral 22 designates a lower rotor 65 casting having an axial opening 23 rotatably receiving the shaft 14. The lower end of the hub of this rotor casting abuts the upper surface of the thrust bearing 21 to be supported thereby and the lower surface of this casting 70 overlies the upper edge of the flange 20 and extends well outwardly therefrom, so that the entrance of rain, water and dust to the bearing housing is prevented. The under surface of the rotor casting 22 is 75 formed with an ear 24 to which is secured one end of a brake band 25, the opposite end of which is connected by an adjustable link 26 to a lever 27 pivoted to the ear. This band 80 embraces the flange 20 of the rotor base and provides a means, when tightened, for holding the rotor against rotation with relation to this base.

The lower rotor casting has a flange 28 upon 85 its upper surface, which is interiorly threaded for engagement with the lower end of a tube 29 surrounding the shaft 14 in spaced relation thereto, this tube having an opening 30 in its side wall through which lubricant may be introduced to the bearings of the lower 90 rotor casting. The upper end of the tube is threaded into a flange 31^a on the hub 31 of an upper rotor casting 32, which hub has an opening 33 through which the shaft 14 is directed. The upper ends of the bores 23 and 33 are counterbored, as at 34, for the reception of roller bearings 35. The upper surface of the hub is abutted by a washer 36 held in position upon the upper end of the shaft by a threaded sleeve 37, which provides 100 means for connecting to the upper end of the shaft a staff or mast 38.

Bolted or otherwise secured at their inner ends to the lower rotor casting are a plurality of seat supporting arms 39, which extend 105 radially from the casting and are approximately horizontally disposed. Secured at their inner ends to the upper rotor casting

are arm braces 40, which extend outwardly and downwardly from the upper casting and have their outer ends bolted to the associated seat supporting arms adjacent the outer ends thereof, as at 41. Seat boards 42 are provided, each of these boards seating at its ends upon plates 43 secured to the ends of the associated seat supporting arms 39. One of these bolts securing the plates in position is 10 preferably the bolt 41 securing the adjacent arm brace 40 to the arm 39 and the ends of the boards are notched at 44 to accommodate this brace. The ends of these boards bearing against the brace tend to prevent deflection 15 of the brace upon the arm. Upon the upper-surface of the end of each board is superimposed a reinforcing plate 45, which is likewise notched to accommodate the arm, as at 46, and is bolted to the associated plate 43 by bolts 47 20 extending through the seat board 42. In this manner, the seats, seat arms and seat braces can be rigidly secured to one another and there is no tendency to twist between the upper and lower castings of the rotor sections. 25 The braces 40 are further rigidly secured to one another by bars 50 extending therebetween in parallel relation to the seats and at such a point that they provide backs for the seats. From one of the arms 49, a lever 51 is 30 pivotally mounted at a point convenient to the adjacent seat board 42 and this lever is connected with the lever 27, as at 52, to provide for operation of the brake. A platform 53 is 35 preferably placed upon the upper surfaces of the arms 39, so as to prevent any accidental contact with the base structure.

It will be obvious that a construction of this character may be very readily and cheaply produced and due to the fact that the bearings thereof are housed, will give excellent 40 service. While the roller bearings 35 are preferably employed, these may be omitted if it is desired that a cheaper structure be produced.

45 Since many changes are possible in the construction hereinbefore set forth without materially departing from the spirit of the invention, I do not limit myself to such specific structure except as hereinafter claimed.

50 I claim:—

1. In a merry-go-round, a base structure, a shaft arising therefrom, a rotor structure engaged with the shaft and including upper and lower castings, a tube surrounding the shaft 55 and maintaining the upper and lower castings in spaced relation and against relative rotation, arms extending outwardly from the lower casting, braces extending outwardly from the upper casting and secured to said arms at the outer ends thereof and seats connecting the outer ends of said arms to one another, said seats being rigidly connected to the arms and having engagement with said braces preventing oscillation 60 of the braces with relation to the arm. 65

2. In a merry-go-round, a base structure, a shaft arising therefrom, a rotor structure engaged with the shaft and including upper and lower castings, a tube surrounding the shaft and maintaining the upper and lower castings in spaced relation, arms extending outwardly from the lower casting, braces extending outwardly and downwardly from the upper casting and secured to said arms at the outer ends thereof, seats connecting the outer ends of said arms to one another, a brake flange carried by the base structure and extending upwardly toward the lower rotor casting, a brake band carried by the lower rotor casting and surrounding said flange and means operable by an occupant of one of said seats for constricting the band upon the drum. 70 75 80 85

3. In a merry-go-round, a base structure, a shaft arising therefrom, a rotor structure engaged with the shaft and including upper and lower castings, a tube surrounding the shaft and maintaining the upper and lower castings in spaced relation, arms extending outwardly from the lower casting, braces extending outwardly and downwardly from the upper casting and secured to said arms at the outer ends thereof, seats connecting the outer ends of said arms to one another, a brake flange carried by the base structure and extending upwardly toward the lower rotor casting, a brake band carried by the lower rotor casting and surrounding said flange, means operable by an occupant of one of said seats for constricting the band upon the flange, said flange combining with the lower rotor casting and the base structure to produce a housing and a thrust bearing within said housing upon which the lower rotor casting rests. 90 95 100 105

4. In a merry-go-round, a base structure, a shaft arising therefrom, a rotor structure engaged with the shaft and including upper and lower castings, a tube surrounding the shaft and maintaining the upper and lower castings in spaced relation and against relative rotation, arms extending outwardly from the lower casting, braces extending outwardly and downwardly from the upper casting and secured to said arms at the outer ends thereof and seats connecting the outer ends of said arms to one another, a plate secured to the outer end of each of said arms upon which adjacent ends of seat sections engage and to which the adjacent ends of the seat sections are secured, adjacent ends of the seat sections being notched to receive the ends of the brace associated with the arm. 110 115 120 125

5. In a merry-go-round, a base structure, a shaft arising therefrom, a rotor structure engaged with the shaft and including upper and lower castings, a tube surrounding the shaft and maintaining the upper and lower castings in spaced relation and against relative rotation, arms extending outwardly 130

from the lower casting, braces extending outwardly and downwardly from the upper casting and secured to said arms at the outer ends thereof and seats connecting the outer ends of said arms to one another, a plate secured to the outer end of each of said arms upon which adjacent ends of seat sections engage and to which the adjacent ends of the seat sections are secured, adjacent ends of the

seat sections being notched to receive the ends of the brace associated with the arm, the securing means connecting the outer ends of the braces to the arms extending through said plates.

In testimony whereof I hereunto affix my signature.

JOHNNY G. C. AKERS.
